RAILWAY CROSSING

Benjamin E. Gallaspay and William E. Gallaspay,
Fort Worth, Tex.

Application June 20, 1932. Serial No. 618,290

6 Claims. (Cl. 246—273)

Our invention relates to railway rail crossings and more particularly to crossings automatically operated by wheels of passing trains; and the object is to provide crossings for trains which will be automatically actuated by the flanges of the wheels of trains passing in either direction. One advantage is that the rails of the railway are held absolutely rigid and certain shifting devices provide continuous surface for the treads of the wheels and by reason of such construction, the pounding of the wheels is eliminated. Other objects and advantages will be fully explained in the following description and the invention will be more particularly pointed out in the claims.

Reference is had to the accompanying drawings which form a part of this application.

Fig. 1 is a plan view of the four units of a crossing.

Fig. 2 is an enlarged plan view of one unit.

Fig. 3 is a plan view of the four shifting blocks for automatic operation.

Fig. 4 is a side elevation of Fig. 2.

Fig. 5 is a perspective view of the two disks which automatically effect the shifting of the two blocks which are remote from the two blocks which are being shifted by a wheel flange.

Fig. 6 is a perspective view of the guiding disks.

Fig. 7 is a plan view of the main frame or holder with the shifting blocks removed and showing by dotted outline the recesses which receive the base flanges of the shifting blocks, the shifting blocks being removed.

Fig. 8 is an inverted plan view of the holder shown in Fig. 7.

Fig. 9 is a side elevation of Fig. 7, partly in section, taken on the line 9—9 of Fig. 7.

Fig. 10 is a vertical section taken on the line 10—10 of Fig. 2, but including two blocks 1 and 2.

Fig. 11 is an exterior elevation of two shifting blocks, the main holding frame being shown in section.

Fig. 12 is a plan view of one of the shifting blocks.

Fig. 13 is an end elevation of the same.

Fig. 14 is a vertical section of the same, taken on the line 14—14 of Fig. 12.

Fig. 15 is a vertical section of the main holding frame and bed plate.

Fig. 16 is a vertical section of the main frame, showing an interior elevation of one corner of the main holding frame.

Fig. 17 is a broken horizontal section of one corner of the main holding frame, showing one of the movable blocks complete.

Similar characters of reference are used to indicate the same parts throughout the several views.

This invention employs four shiftable blocks of special shapes for each of the four crossings of the rails. These blocks are shiftable automatically by the flanges of passing wheels. The flange of a wheel shifts two of the blocks and the shifted blocks shift the other two blocks. The blocks form parts of the treads for the wheels and the flanges of the wheels project far enough in advance so that the blocks are shifted in place for the treads before the treads run on the blocks.

The drawings show blocks 1, 2, 3, and 4 and a quadrangular frame 9 is rigidly mounted on a base 5' for preventing displacement of the blocks. The holding frame 9 has passage ways for the four approaches of the wheel flanges and for the four exits of the wheel flanges and the holding frame 9 has its central part cut away to form the block assembly space 23. The holding frame has portions 5, 6, 7, and 8 which form parts of the treads for the wheels. The treads of the wheels roll off of the rails 24 onto the portions 5, 6, 7, and 8. The blocks 1, 2, 3, and 4 have raised triangular portions 10 which cooperate with the surfaces 5, 6, 7, and 8 to complete the rail treads across the crossings. The blocks 1, 2, 3, and 4 have base members 13 which project under and support the surface members 5, 6, 7, and 8 of the holding frame 9. The blocks 1, 2, 3, and 4 are supported and slide on a base plate 5' which may be made rigid with a bed plate 22. The blocks 1, 2, 3, and 4 have beveled approaches 11 to act as guides for the wheel flanges to start in between two blocks. These beveled approaches are at all four approaches of the wheels. The under-cuts in the members 5, 6, 7, and 8 for the members 13 of the blocks are shown at 25. The wheel flange 32 actuates the blocks 1, 2, 3, and 4 and the flange members 13 are projected under the members 5, 6, 7, and 8 as far as the boundary wall 14 which is the back wall of the under-cut slot 25. The undersides of the blocks 1, 2, 3, and 4 are beveled at 26 and the upper edges of the flange arms 27 are beveled at 12 so that the blocks will really slide under the members 5, 6, 7, and 8.

Means are provided so that one block will actuate another block. Disks 15 and 16 are rotatably mounted on an upright spindle 28. The peaks of the blocks 1, 2, 3, and 4 are under-cut so that the disks 15 and 16 will project slightly thereunder. Recesses 19 are formed in the blocks 1—4 and the disks 15 and 16 have lugs

17 and 18 which are adapted to project into the recesses 19. By such construction, when one of the blocks 1-4 is actuated, it will actuate another block automatically. Consider Figs. 3 and 5. The lugs 18 occupy the recesses 19 in blocks 2 and 4 and the lugs 17 occupy the recesses in blocks 1 and 3. If the wheel flange 32 enters at the bottom of Fig. 3, the blocks 3 and 4 will be spread by the flange 32. The block 3 by reason of the recess 19 will move the lug 17 and the lug 17 on the opposite side of the disk 15 will actuate the block 1 and the block 4 by reason of the recess 19 therein will actuate the lug 18 and so actuate the disk 16 and the disk 16 by reason of the lug 18 on the opposite side of disk 16 will actuate the block 2. All four blocks 1-4 will be spread for the passage of the wheel flange 32 and simultaneously the tread surfaces 10 will be brought in line with surfaces 6 and 7 to complete continuous track surfaces for the tread of the passing wheel from the rails 24 or from the rails 20 and 21. Similar operations take place when a wheel flange enters any one of the approaches to the crossing and strikes the beveled surfaces 11 of the blocks 1-4.

In these operations the blocks 1-4 are guided by the flanges 13 moving along the boundary walls 14 within the cut-outs or spaces 25 in the main frame 9, and also by the portions 10 of the blocks moving against the edges of the tread supporting members 5, 6, 7, and 8 of the main holding frame. The arms 27 are limited in movement and stop against the abutments 29 of the main holding frame 9. The blocks 1-4 have lips 31 which move against or along the sides of an abutment 30 which is rigid with the bed plate 5'. The flanges of the wheels tend to force the blocks 1-4 outwardly and the abutment 30 and the lips 31 serve further to prevent inward movement of the blocks 1-4. The abutment 30 thus serves as an additional guide for the blocks 1-4. The guard rail 33 is a necessary element in the operations of the crossings. The guard rail sections abut against the main holding frame 9 in the same manner as the rails 24. The main holding frame 9 is secured to the base plate 5' by bolts 34 and nuts 35.

What we claim is:—

1. A railway crossing comprising a base plate interposed between abutting rail sections of a track crossing, a main holding frame rigid with said base plate and abutting against said rail sections on all sides thereof and provided with a central cavity and channels leading from said cavity outwardly through the sides of said frame and having undercut passages about said cavity and channels, shiftable blocks mounted in said cavity and channels and provided with portions thereof adapted to be moved in said undercut passages by flanges of passing wheels and disks pivotally mounted in said frame and operatively connected to said blocks whereby all the blocks are automatically-simultaneously shifted.

2. A railway crossing comprising a base plate interposed between abutting rail sections of a track crossing, a main holding frame rigid with said base plate and abutting against said rail sections and provided with cross channel passages for the flanges of passing wheels and having a central cavity in communication with said passages, and shiftable blocks mounted in said cavity and each block having a pair of arms at angles to each other projecting in said channels to be

actuated by flanges of passing wheels for opening a passage in either direction through said holding frame, a pair of disks pivotally mounted in said frame and cooperating with said blocks for causing said blocks to be simultaneously shifted, said blocks and said frame being provided with interlocking and stopping means for forming a continuous tread surface between said rail sections. 80

3. A railway crossing comprising a base plate interposed between rail sections of a track crossing, a main holding frame rigid with said base plate and abutting against said rail sections on all sides and provided with a central cavity and cross channel passages for the passage of flanges of passing wheels, shiftable blocks mounted in said cavity and provided with beveled supporting arms projecting in said channels to be actuated by the flanges of passing wheels from all directions, and guiding and stopping and actuating means operatively connecting said blocks and holding frame whereby all of said blocks are automatically-simultaneously shifted. 85

4. A railway crossing comprising a base plate interposed between rail sections of a railway track crossing, a main holding frame rigid with said base plate and abutting against rail sections on all sides and provided with a central cavity and cross channel passages for the passage of flanges of passing wheels, shiftable blocks mounted in said cavity and provided with supporting arms projecting in said channels to be actuated by the flanges of passing wheels, said blocks and said holding frame being provided with interlocking means for forming a continuous tread passage from one rail section to another, and guiding and actuating means operatively connecting said blocks and frame whereby all of said blocks are automatically-simultaneously shifted. 100

5. A railway crossing comprising a base plate interposed between rail sections of a track crossing, a main holding frame rigid with said base plate and abutting against said rail sections on all sides and provided with a central cavity and cross channel passages for the passage of flanges of passing wheels, shiftable blocks mounted in said cavity and provided with supporting arms projecting in said channels to be actuated by the flanges of passing wheels from all directions, said blocks and said holding frame being provided with interlocking and stopping means 115 for forming a continuous tread surface from one rail section to another, and guiding and actuating means operatively connecting said blocks and holding frame whereby all of said blocks are automatically-simultaneously shifted. 120

6. A railway crossing comprising a base plate interposed between rail sections of a track crossing, a main holding frame rigid with said base plate and abutting against said rail sections on all sides and provided with a central cavity and cross channel passages for the passage of flanges of passing wheels, shiftable blocks mounted in said cavity and provided with supporting arms having beveled approaches and projecting in said channels to be actuated by the flanges of passing wheels from all directions, and guiding and stopping and actuating means operatively connecting said blocks and said frame whereby said blocks and frame form a continuous tread surface from one rail section to another. 135
